CLAIM

The ornamental design for a combined vacuum cleaner and scrubbing brush, as shown.

DESCRIPTION

FIG. 1 is a top, front and right side perspective view of a combined vacuum cleaner and scrubbing brush showing our new design;

FIG. 2 is a bottom, rear and left side perspective view thereof;

FIG. 3 is a top plan view thereof;

FIG. 4 is a left side elevational view thereof; and

FIG. 5 is a bottom plan view thereof.

FIG. 5
